MOLDING CORE

Wallace A. Evans, David W. Evans, and Leslie J. Sims, Penarth, Wales; said Sims assignor to said Wallace Alfred Evans and said David Wallace Evans

Application March 13, 1950, Serial No. 149,334

2 Claims. (Cl. 25—128)

1

This invention relates to moulding cores and more especially to cores for use in moulding hollow concrete structural members.

It is nowadays considered desirable that cores for moulding hollow concrete structural members should be withdrawable after use and be suitable for repeated use in moulding further members. Various constructions of cores adapted for repeated use in this manner have been proposed and used and it is an object of this invention to provide an improved core which is both comparatively simple in construction and economical in use.

According to the invention a collapsible core for use in moulding hollow concrete and similar members comprises a number of oppositely disposed pairs of rigid members, the members of each pair being relatively movable towards and away from each other so as to vary the cross-sectional dimensions of the core, and means adapted to hold the members of each pair when said members have been moved relatively away from each other.

Further according to the invention a collapsible core for use in moulding hollow concrete and similar members comprises rigid side members which are bodily relatively movable from a position in which they hold other side members spaced fully apart to a position nearer one another in which they permit of relative movement of said other side members towards each other.

The invention will be described by way of example with reference to the accompanying drawings in which:

Fig. 1 is an end elevation with parts broken away.

Fig. 2 a fragmentary plan view.

Fig. 3 a sectional elevation on the line III—III of Fig. 1.

Fig. 4 is a sectional elevation on the line IV—IV of Fig. 1 and

Figs. 5a, 5b are diagrammatic views illustrating a device for preventing lateral distortion of side members in a long core during moulding.

Referring to the accompanying drawings, a core comprises two flat plate members or outer members 1, 2 each having lateral edge portions 1a, 2a which are so shaped that when the plates are arranged opposite one another the inner surfaces of the edge portions on the top plates on each side of the core converge. Two tubular side or inner members 3, 4 are disposed within the plates or outer members 1, 2 so that when the side or inner members 3, 4 are moved apart they force the plates or outer members 1, 2, apart. When the side or inner members are moved together the plates 1, 2 are able to move towards one another until the flat portions of the plates ride on the side members. Both the plates 1,

2

and the side members 3, 4 extend over the length of the core.

The relative movements of the plates or outer members and side or inner members are limited by means of end plates disposed at each end of the core, one of these end plates 5 being shown and it is to be understood that the end plate at the other end is similar to the plate 5. The end plate 5 is provided with slots 6, 7 which are each closed at both ends and pins 8, 9 fixed to and projecting from the side or inner members engage in these slots. Similar slots 10, 11 which extend at right angles to the direction of the slots 6, 7 are also provided in the end plate and pins 12, 13 which are fixed to and extend from blocks 14, 15 fixed to the plates or outer members 1, 2 engage in the slots 10, 11.

The pins 8, 9 are suitably formed by screw-threaded bolts which are disposed in discs 16, 17 which are fixed in the ends of the side or inner members 3, 4 by counter-sunk screws 18 as shown in Fig. 4. A hole 19 in each disc may be provided for the reception of a duct so that steam or other hot fluid may be circulated through the side or inner members in order to facilitate rapid hardening of the concrete. Spring clips 20 are shown provided for the purpose of holding the bolts 8, 9 in position but the bolts may be otherwise secured in position in the discs, for example they may be cast in, and, in order to prevent the bolts from turning, they may be provided with flats on their shanks, the bores in the discs being correspondingly shaped.

The blocks 14, 15 may be secured to the outer members 1, 2 by countersunk screws 21 and screw-threaded bolts are disposed in the blocks to form the pins 12, 13. Spring clips 20 are also arranged to hold the bolts 12, 13 in position in like manner to the arrangement for the bolts 8, 9. Nuts 22 are provided to engage the bolts 8, 9 and 12, 13 in order to locate the bolts in their outermost position in the slots 6, 7 and 10, 11. The lengths of the slots 6, 7 are such that the side or inner members 3, 4 are prevented from moving apart to such an extent that the inclined surfaces on the plates or outer members 1, 2 which bear on the side or inner members are able to move apart to a distance equal to the outer diameter of the side or inner members. Each flat outer member 1, 2 is provided with an inwardly projecting strengthening rib 23.

When the core is arranged for use the side or inner members 3, 4 are moved manually apart to the greatest distance permitted by the slots 6, 7 and locked in this position by tightening the nuts 22 on the bolts 8, 9. This movement of the side or inner members is followed by a corresponding movement of the flat outer members 1, 2 and these members are also held fixed in position by tightening the nuts 22 on the bolts 12,

13. After a concrete member has been moulded and the concrete is sufficiently set the nuts 22 are slackened and the side or inner members and the flat outer members moved together to collapse the core.

In order to facilitate removal of the core from a moulded concrete member the outer surfaces of the flat outer members 1, 2 are provided with open grooves 24 and after the core has been prepared for use by moving the side or inner members 3, 4 and the flat outer members 1, 2 apart and tightening the nuts 22, a sheet of paper or like flexible thin material is wrapped round the core. By this means the core, after being collapsed, can readily be withdrawn from a moulded member.

Although the side or inner members 3, 4 are shown as true cylinders it will be appreciated that these members may have other curved shapes while the flat plates or outer members may be formed, for example, with recesses on their inner surfaces the forms of the different members in each case, however, providing a wedge-like action whereby the members of one pair are spaced more widely when the member of the other pair are moved apart.

Where the side or inner members 3, 4 are long in relation to their cross-sectional area and there may be a danger of these members bending inwardly under the stresses imposed by concrete during setting, the arrangement illustrated by Figs. 5a and 5b may be employed. In this arrangement an arm 25 is pivotally mounted on the strengthening rib 23 on the lower flat outer member 2. The arm 25 carries transversely projecting rigid arms 26, at the free end of each of which is mounted a roller 27. These rollers 27 and arms 26 are so dimensioned that when the side or inner members 3, 4 have been moved fully apart the rollers will just bear on these side members after the arm 25 has been raised from a position in which it lies along the flat outer member 2, as shown in broken lines in Fig. 5b, to the upright position as shown in full lines in Fig. 5a and in broken lines in Fig. 5b. The desired movements of the arm 25 and rollers 27 may be effected by a cord 28 which is fastened to the upper end of the arm 25 and which protrudes at both ends of the core as indicated in Fig. 5b.

An arm 25 and rollers 27 may be arranged at an end of the core so that a number of cores may be placed end to end for the purpose of moulding a beam longer than one or more cores. In this use of the core provided by the invention, the nuts 22 at adjacent ends of adjacent cores are not tightened after the arms 25 have been erected, the nuts at the outer ends of the two end cores only being tightened, the core side members of course having been previously spaced for moulding.

It will be understood that the core described may be used for moulding reinforced concrete members, the reinforcement being disposed in normal manner.

The reinforcement plate is also provided with lugs which engage between the side members 3, 4 to prevent lateral displacement thereof.

It is contemplated that the core provided by the invention will be employed in moulding ma-

terials other than concrete for example the materials known as plastics.

We claim:

1. A collapsible core for use in moulding hollow concrete and similar members which comprises a pair of oppositely disposed rigid outer members of which at least one member has at each longitudinal edge portion a surface which is inclined towards and faces the adjacent edge portion of the other member of the said pair, a pair of oppositely disposed rigid inner members each having a curved outer surface and disposed loosely between said outer members, the said inner members being bodily movable apart to cause the said curved outer surfaces to ride on the said inclined surfaces and thereby to force the outer members apart, means limiting the movement apart of the inner members, stop means, means pivotally mounting said stop means on one of the outer members and an actuating member operable from outside the core to move the said stop means into and from a position between the inner members in which the stop means abut on both the members of the inner pair.

2. A collapsible core for use in moulding hollow concrete and similar members which comprises a pair of oppositely disposed rigid outer members of which at least one member has at each longitudinal edge portion a surface which is inclined towards and faces the adjacent edge portion of the other member of the said pair, a pair of oppositely disposed rigid members each having a curved outer surface and disposed loosely between said outer members, the said inner members being bodily movable apart to cause the said curved outer surfaces to ride on the said inclined surfaces and thereby to force the outer members apart, an end plate disposed at each end of the core, the said end plate being provided with closed guide slots, pins projecting from each member of each pair and entering the slots, stop means, means pivotally mounting said stop means on one of the outer members and an actuating member operable from outside the core to move the said stop means into and from a position between the inner members in which the stop means abut on both the members of the inner pair.
